DESIGN FOR A HAIR CLIP OR SIMILAR ARTICLE

Gloria Goldman, New York, N. Y.

Application May 7, 1945, Serial No. 119,431

Term of patent 3½ years

(Cl. D86—10)

To all whom it may concern:

Be it known that I, Gloria Goldman, a citizen of the United States of America, residing in New York city, county of New York, and State of New York, have invented a new, original, and ornamental Design for a Hair Clip or Similar Article, of which the following is a specification, reference being had to the accompanying drawing, forming part thereof, wherein clip or similar article showing my new design.

Figure 2 is a side elevational view of the hair clip or similar article shown in Figure 1.

The views are lined for contrasting colored areas.

I claim:

The ornamental design for a hair clip or similar article, substantially as shown and described.

GLORIA GOLDMAN.
